UNITED STATES PATENT OFFICE.

LESLIE WOOD SEWARD, OF ATLANTIC CITY, NEW JERSEY, ASSIGNOR TO RECORD BOOK CABINET COMPANY, A CORPORATION OF NEW JERSEY.

BOOKCASE.

Application filed February 27, 1926. Serial No. 91,081.

My invention relates to book-shelving, or cabinets, designed more especially for public record-books. It has for its objects a cabinet provided with a number of superposed sliding shelves of a construction adapted to combine maximum strength and comparative lightness, the individual shelves being formed and associated with devices to reduce friction to the minimum and in which the shelves will be limited in their extent of withdrawal to prevent complete accidental withdrawal, and in which also the handles to the shelves will serve as stops to prevent books resting on the shelves from slipping forward from off the shelves, and also prevent replacing the books in the cabinet except by laying the book on the shelf and then sliding the shelf into the cabinet and thus avoiding abrasion and wear on the book binding; and also in which the shelves will be formed so as to make it possible to grasp the books with the hands so as to more easily lift the books from the shelves when desired to remove the books.

To the accomplishment of each of the several objects mentioned, and other objects hereinafter made to appear, the invention consists in the various features hereinafter particularly described and then sought to be clearly defined by the appended claims, the preferred details of construction for embodiment of the invention being illustrated in the accompanying drawing.

In the drawing, Figure 1 is a front elevation of a portion of a cabinet showing three superposed shelves but of which there may be any desired number, depending on the height of the cabinet;

Figure 2 is a vertical transverse section through Figure 1;

Figure 3 is a horizontal section, on an enlarged scale, with parts broken away;

Figure 4 is a side view of Figure 3;

Figure 5 is a detail cross-section through parts illustrated;

Figure 6 is a perspective of one of the sliding shelves, removed from the cabinet and showing in dotted lines a book resting thereon.

In the drawing the numeral 1 designates side walls of the cabinet, which preferably are formed of suitable metal. At the front, open side of the cabinet, at opposite sides thereof, are upright standards 2, preferably tubular in formation, and having side walls

connected thereto by brazing, or otherwise, and which at their lower ends may rest upon the base 3 preferably formed of channelled metal and suitably attached to opposite side walls of the cabinet, for instance, by angle plates 4. Mounted to slide in the cabinet, on roller bearings, are shelves 5 three being illustrated but of which there may be any desired number. These shelves are preferably metal and each formed at its front with a downwardly, rearwardly and upwardly bent flange 6 to give strength to the shelf and afford a base for attachment of operating handles 7.

Each shelf is supported to slide on ball-bearing rollers 8 which are carried by plate-rails 9 extending inwardly from opposite side walls of the cabinet and suitably attached thereto, the inner ends of plates 9 having a horizontally extending flange 10 which is practically the length of the cabinet from front to rear and serves as a guide for a roller 11 connected with the shelf so as to steady the shelf in its forward and backward movements. Two of the rollers 11 are employed and each journaled in a Z-shaped bracket 12 preferably supported from the bottom of the shelf and attached thereto, preferably near its rear, by brazing, or otherwise, and the lower horizontal member or flange 13 of the brackets will preferably overlap the adjacent portion of plate-rail 9 so as to guard against tilting of the shelf in its sliding movements. The shelf rests upon and travels over the rollers 8, and its rollers 11 travel along the flange of plate-rail 9 so that the shelf has ball-bearing rollers to steady it and check vertical vibrations in being moved in and out, and tilting will be prevented by contact of the bracket flange 13 with the bottom of plate-rail 9.

The rear portion of each shelf is provided with a book-stop 14, which may be in the form of a channel plate attached by brazing, or otherwise, to the shelf; and at opposite sides, at or adjacent to the rear, the shelf is provided with laterally projecting lugs 15 riveted or otherwise attached to or made integral with flanges 16 depending below the bottom of the shelf so as to contact with stop-pins or lugs 17 positioned at the sides of the cabinet at or adjacent to the open front of the cabinet for the purpose of limiting the withdrawal of the shelf and thus prevent its accidental complete withdrawal.

from the cabinet. For the purpose of facilitating the easy lifting and removal of comparatively heavy record books from the shelves, each shelf is formed with recesses 5 18 in its opposite edges so that the fingers may pass beneath the book when the book is to be grasped by the hands for removal from the shelf.

The handles 7 project above the surface 10 or plane of the shelf so as also to serve as a stop to prevent a book on the shelf from sliding or being pulled from off the shelf and to maintain the book in position on the shelf in backward and forward movement of 15 the shelf, thus absolutely preventing abrasion and wear on the book binding. The upper portion of the handle is bent or curved outward as shown so as to afford an easy grip for the hand in sliding the shelf out or 20 in, and also preventing the books from being shoved into place and insuring them being placed on the shelves in their replacement into the case.

I have illustrated and described with particularity the details of the various parts constituting an embodiment of the invention but the various features may be changed in details without departing from essential features although the details as illustrated 30 are preferred.

A book-shelving, or cabinet of shelves, formed as described is especially well adapted for offices where records are kept for frequent reference, and where as a rule the record books are relatively large and heavy, and therefore, it is desirable to have the record books removable from the shelving or case, and replaceable with the minimum abrasion or wear on the book covers or 35 bindings. The structure also makes it possible to build the shelving entirely of metal or practically so, and to have it substantial in strength as well as durable in longevity, and with the shelving easily slidable with 40 steadiness and minimum of vibration in use.

Having described my invention and set forth its merits what I claim is:—

1. A book-case comprising stationary plate rails extending inwardly from the 50 sides of the case and formed with upwardly and laterally inwardly-extending portions at their inner ends, rollers journaled on the upwardly-extending portions of said rails, a shelf resting and slidable on said rollers, and brackets mounted on the under-face of 55 said shelf, said brackets carrying rollers bearing against the laterally-extending portion of the rail carrying the shelf-supporting rollers.

2. A book-case comprising a plurality of 60 spaced slidable-shelves forming compartments therebetween, means for supporting each shelf, and a handle attached to the front of each shelf and extended above its horizontal plane to serve as a guard for 65 the book to be supported upon the shelf and having its upper portion bent outwardly.

3. A book-case comprising a plurality of spaced slidable-shelves forming compartments therebetween, each shelf formed with 70 recesses at its opposite sides to permit fingers of the hand to pass beneath a book resting upon the shelf to lift the book, means for supporting each shelf, and a handle attached to the front of each shelf 75 and extended above its horizontal plane to serve as a guard for the book to be supported upon the shelf and having its upper portion bent outwardly.

4. A book-case comprising a plurality of 80 spaced slidable metal shelves forming compartments therebetween, each shelf being formed at its front with a reinforcing depending flange, means for supporting each shelf, and a handle attached to the depending flange at the front of each shelf 85 and extending above the horizontal plane of the shelf to serve as a guard for the book to be supported upon the shelf.

5. In a record-book cabinet, slidable 90 metallic shelves, members extending inwardly from the sides of the cabinet, rollers supported in fixed positions at the inner ends of the inwardly extending members and having rolling contact with the under 95 faces of the shelves, brackets depending from the under face of the shelves and extending from the front to the rear of the shelves, rollers carried by said brackets and having rolling contact with portions of the inwardly extending side members, said brackets and rollers carried by the inwardly extending members cooperating to reinforce the metallic shelves.

6. A book-case comprising a slidable 100 shelf, supports carrying rollers on which the shelf rests and is slidable, brackets supporting rollers from the shelf in position to engage a portion of the support which carries the shelf supporting rollers, and a handle attached to the front of the shelf and extended above the horizontal plane of the shelf to serve as a guard at the front of the shelf.

In testimony whereof I affix my signature.

LESLIE WOOD SEWARD.
